Attorney.

UNITED STATES PATENT OFFICE.

JOSEPH WACHTELSCHNEIDER, OF NEW YORK, N. Y., ASSIGNOR TO GODFREY P. SCHMIDT, OF NEW YORK, N. Y.

FIGURE TOY.

1,148,266.

Specification of Letters Patent. Patented July 27, 1915.

Application filed January 16, 1915. Serial No. 2,548.

To all whom it may concern:

Be it known that I, JOSEPH WACHTELSCHNEIDER, a citizen of the United States, residing at New York, in the county of New York and State of New York, have invented certain new and useful Improvements in Figure Toys, of which the following is a specification.

This invention relates to figure toys, which are usually made by stamping a small animal, ordinarily a horse, from a sheet of metal, and providing the same with a weighted rocking support whereby when placed upon the edge of a table, the horse may be given an up and down rocking movement, which will be maintained for some little time by the pendulous action of the weight, for the amusement of little children.

The object of this invention is to produce a toy of the structural nature stated, in which the figure of a rider upon the animal is also pivoted and weighted and has an individual movement during which it rises and descends in the saddle as the animal figure rocks.

It is also an object of this invention to provide a rocking support made of a single piece of wire, and having parts of special construction and arrangement, rendering it very cheap to make. The rocking support includes a clamping device enabling it to be attached to the animal figure at any point, and permitting the figure to be held in different positions.

The various parts combined to make up this invention, are set out in the accompanying drawings, of which—

Figure 1 represents a side view of all the parts assembled. Fig. 2 is a front view of the straight or upright members of the rocking support, showing the clamping rings and the triangular base upon which the whole rests. The curved portion of the rocking support is cut off on the line $y-y$ of Fig. 1, and a portion of the animal figure is shown in section between the clamping rings. Fig. 3 is a vertical section on the broken line $x-x$ of Fig. 1, and shows the lower extension of the riding figure which is provided with a weight located in a pocket shown in section, with which the animal figure is equipped.

Throughout the drawings and description the same letter is employed to refer to the same part.

Considering the drawings, the edge of a table or the like is marked A, and upon it is arranged a rocking weighted support made of a continuous piece of wire and having the curved portion B provided at its lower end 60 with a weight b. The weight is located under the edge of the table as shown, and upon the table is erected the upright or straight portion D of the wire, that is furnished at its lower end with a triangular base or foot 65 d. At the upper end of the curved portion B of the wire, it is given one or more turns C around the straight portion D, and the wire is then continued in a second straight portion E into a clamping ring e. The portion E of the wire which extends downwardly from the ring e to the turns or twists C, it will be noted, is less in length than the portion D. After completing the clamping ring e, the wire is given a return bend F, 70 and a second or twin clamping ring f is formed by the side of the ring e. The rings are located at the top of the straight portion D.

A piece of metal G is stamped out and 75 lined to represent a small horse or pony, and another piece of stamped metal g is intended pictorially to be the riding figure.

A pivot pin H, as best shown in Fig. 3, passes through a downwardly-extended portion of the riding figure, and a weight J is attached to its lower part. Both the weight and the lower extension of the riding figure are arranged in a pocket K with which the animal figure is provided. The saddle k, 80 and the leg and foot j of the riding figure are drawn or printed upon the outside of the pocket and horse G. It will be noted, therefore, that the leg and foot of the riding figure are stationary.

In the operation of this invention, any part of the animal figure may be held between the clamping rings, as shown in Figs. 1 and 2. In the drawings the horse is represented in substantially a straight position, 100 but, it is thought to be clear that, assuming the position illustrated to be the position of balance due to weight B, the body of the animal may be inclined upwardly or downwardly, by changing its position in the 105 clamping rings.

If in the position shown, the horse be given by hand an impulse up or down, the rocking movement on the triangular base d will be commenced and kept up for a consid- 110

- erable time. As the head portion of the horse rises from the position illustrated, the body of the rider rises in the saddle *k*. This action is brought about by placing the pivot 5 pin *H* at a distance to the left of a vertical middle line passing through the riding figure. As the rider alternately rises and falls in his saddle, he appears to be striking at the animal figure with the whip in his hand.
- 10 Having now described this invention, the parts thereof, and the mode of its operation, what I claim is:—
1. In a figure toy, a sheet metal animal figure provided with a pocket open at the 15 top, a riding figure having a downwardly-extending portion, a weight attached to the said portion, the said portion and weight being located in the said pocket, a pivot pin passing through the sides of the pocket and 20 through the said downwardly-extending portion of the riding figure, and a weighted rocking support attached to the said animal figure.
2. In a figure toy, a sheet metal animal figure provided with a pocket open at the 25 top, a riding figure having a downwardly-extending portion, a weight attached to the said portion, the said portion and weight being located in the said pocket, a pivot pin passing through the sides of the pocket and 30 through the said downwardly-extending portion of the riding figure at one side of the vertical middle line of the said riding figure whereby the said figure rises in its seat as 35 the animal rocks, and a weighted rocking support attached to the said animal figure.
3. In a figure toy, a rocking support comprising a straight portion provided at the

top with spring clamping devices, a curved portion having one end connected with the 40 straight portion between the ends of the said straight portion, and a weight connected with the other end of the said curved portion.

4. In a figure toy, a rocking support comprising a continuous piece of wire having a straight portion, twin clamping rings located at the top of the said straight portion, a portion extending downwardly from the rings and parallel with the said straight 45 portion and less in length than the said straight portion, a curved portion extending downwardly and outwardly from the said downwardly-extending portion, and a weight attached to the lower end of the 50 curved portion.

5. In a figure toy, a rocking support comprising a continuous piece of wire having a straight portion provided at its lower end with a triangular base, twin clamping rings 55 located at the top of the said straight portion, a portion extending downwardly from the rings and parallel with the said straight portion and less in length than the said straight portion, a curved portion extending 60 downwardly and outwardly from the said downwardly-extending portion, and a weight attached to the lower end of the 65 curved portion.

In testimony whereof I affix my signature 70 in presence of two witnesses.

JOSEPH WACHTELSCHNEIDER.
